CHARLES B. GOODSTEIN, OF BROOKLYN, NEW YORK, ASSIGNOR TO BELLA GOODSTEIN,
OF NEW YORK, N. Y.

STAPLE AND METHOD OF DRIVING THE SAME

Application filed January 19, 1929. Serial No. 333,701.

My invention relates to staples for securing together sheets of paper, cardboard, fabrics and various other materials, and to a novel method of driving the staples. Staples have been widely used for securing papers together and also for securing various other kinds of materials and there are various machines on the market for driving and applying staples. As far as I am aware such machines are divided into two general classes, those of one class having, in addition to the means for driving the staples, a lower member or anvil with which the driving plunger cooperates, the anvil serving to turn or clench the staples after they have passed through the material which is being stapled. Another class of machine is that in which the driving means is employed without a base or anvil, in which case the staples have been driven straight into the material and have not been clenched. This type of machine, commonly called a tag machine, is generally used for tacking tags onto boxes, freight cars, etc., for tacking curtain materials onto the curtain rollers and in various other uses where the staple does not have to be clenched. With the first type of machine it is not possible to apply staples to a closed box because it is not possible to get the anvil inside the box to complete the clenching operation. In the second type of machine, or tag machine, there is no part used for clenching the staple.

The object of my invention is to provide a staple and to provide a method of driving the same which will permit staples to be driven through material from one side only and to cause the staple to clench after passing through the material. By employing the present invention it is possible to staple together the flaps or the cover and body of boxes by means of a device which will operate entirely from the outside of the box. It is, therefore, possible to staple flaps or other portions of the box after the latter has been closed, because the clenching of the staple is

accomplished without any anvil or other instrumentality on the interior of the box. As far as I am aware, this is the first instance where staples have been driven through material and clenched by operations carried on from one side only of the material which is stapled. The staple forming the subject of my invention is so formed that when it is driven under the control of devices on one side of the material the prongs of the staple are compelled to not only pass through the material being stapled, but to bend in such manner as to cause the ends to be clenched on the inner side of the material. The advantage of the present invention is that boxes and packages may be rapidly stapled after the contents have been packed therein and the boxes have been closed. The staple forms a more dependable and a stronger means for retaining boxes and packages in closed condition for shipment than the ordinary pasted paper strips now in general use. In addition, the present staple serves as a seal because the staple cannot be removed from a container without showing marks indicating that the package has been tampered with. Once the staple has been applied, that is, driven through the material and clenched on a closed container, access cannot be had to the interior of the container to unclench the staple.

The only way the staple can be removed is by forcibly pulling it out of the material of the container and this will partially destroy the material and show that the package has been tampered with.

In the drawing forming part of this application,

Figure 1 is a vertical, sectional view showing the tools employed in driving staples in accordance with the present invention,

Figure 2 is a perspective view of a portion of a strip of staples embodying my invention,

Figure 3 is a vertical, sectional view show-

ing the staple in position to be driven with the tools applied and ready for the commencement of the driving operation.

Figure 4 is a similar view showing the staple driven through the material and undergoing the clenching operation,

Figure 5 is a similar view showing the staple at the completion of the clenching operation,

16 Figure 6 shows the staple completely applied and the tools withdrawn,

Figure 7 is a perspective view of a modified form of staple strip embodying my invention,

15 Figure 8 is a view similar to Figure 3 but showing the staple ready to be driven without the member for supporting the center of the staple,

Figure 9 is a view similar to Figure 8 but 20 showing the staple completely driven, and

Figure 10 is a sectional view through a container showing the staple applied.

I will first describe the form of my invention shown in Figures 1 to 6 inclusive.

25 In this form of the invention I have shown the staples formed of sheet material and arranged in close parallel relation to constitute a strip from which the individual staples may be removed as they are driven. The 30 individual staples in this strip may be held together by any of the means now employed for holding staples in strip form in connection with the plain staples in general use; that is, by applying a coating of enamel or 35 similar material which will secure the individual staples together at their edges with sufficient tenacity to enable the staples to be handled as a strip until they are driven.

Each staple consists of a preferably flat 40 plane central portion 1 from which extends upwardly at each side an arched or circular portion 2, these circular portions being adapted to form the prongs or legs of the staple. Preferably the outer free ends of these arched 45 portions are cut at an angle, as shown at 3 to form pointed ends for piercing the material. Preferably these pointed ends terminate about in the same horizontal plane as the lower surface of the middle portions 1 of the staples.

50 In driving this form of staple the tools shown in Figures 1 to 6 inclusive may be used. These consist of a vertically moving plunger 4 which serves to drive the staples 55 and this plunger reciprocates in the bore of a sleeve 5. There is a small member 6 which forms a temporary support or anvil under the middle portion 1 of the staple and this member is movable laterally as it is to be withdrawn 60 from the staple before the clenching operation has been completed. Where the material to be stapled has a hard surface into which the central portion of the staple will not sink too far, the anvil member 6 may be 65 omitted so that the central portion of the

staple rests against the material being stapled.

The staple strip is fed onto the anvil member 6 as shown in Figure 3 by any suitable feeding mechanism, such as is commonly used in stapling machines, so that the flat, intermediate portion 1 of the staple rests on the top surface of the anvil member 6 above the material which is to be stapled.

In Figures 3 to 6 I have shown two sheets 7, 8 of cardboard or corrugated board lying face to face, and these may be stapled together by operations carried on from one side of the sheets. These sheets may be overlapping flaps of a box, as shown in Figure 10, which could not otherwise be stapled because in previous practice an anvil had to be used on opposite sides of the sheets to the plunger. Assuming that the staple has been fed onto the support 6, as shown in Figure 3, the arched portions 9 of the staple project at each side and rest against or near the inner surface of the sleeve 5 which is in reality a die member. The plunger 4 which lies above the staple is now moved downwardly in order to press downwardly on the upper portions 9 of the arched prongs. As this pressure is applied by the plunger, the staple has a tendency to be flattened as the plunger presses on the top of the arches 9. The central portion of the staple cannot descend because it rests on the support 6. The free ends of the prongs of the staple cannot spread because they are confined by the die member 5 in which they are enclosed. As the plunger goes down, therefore, as shown in Figure 4, the prongs of the staple under the action of the plunger and under the co-operating action of the die member 5 first pierce the sheets 7, 8 of the corrugated board, and then continue in a circular direction, so that the prongs, after passing through the sheets of corrugated board, move toward each other, as shown in Figure 4. About this time and before the top of the staple, that is, the portion remaining on the outside surface of the corrugated boards, becomes fully flattened, the member 6 is withdrawn laterally.

The plunger continues its downward motion, as shown in Figure 5, so that the portion of the staple 10 above the corrugated board is finally flattened against the latter about the time the ends of the prongs of the staple approach each other, or touch, as shown in Figure 5. Following this operation, the plunger and die are removed, as shown in Figure 6, together with the supporting member 6, and the operation of stapling is now completed. It will be observed that the operations of driving the staple through the corrugated boards and of turning or clenching the prongs inside the same are carried out by operations performed entirely on one surface of the material which is stapled.

If these members are flaps of a box or carton, or the flange and the body of a box, the operations above described may be performed after the box or carton has been filled with 5 the contents and closed. The shape of the staples, together with the tools employed, cause the prongs to pierce the material which is being stapled and to clench without the use of an anvil on the opposite side of the 10 material to that of the plunger.

In Figures 7, 8 and 9 I have shown the staple strip somewhat modified, so that the under support 6 referred to in the previous 15 description need not be placed as previously described. In this form the staples are formed as a strip with a continuous connecting piece or back member 11 similar to staple strips heretofore in use. The prongs 12 in this case, however, are arched, the same 20 as in the first form, and have their ends 13 pointed, but there is a space between each pair of prongs indicated as slots 14 in Figure 7, so that an individual staple may be cut 25 off the strip leaving all the remaining staples connected by the longitudinal member 11.

In this case the intermediate portion or 30 rib 11 of the staple will be supported on a bar similar to the manner in which the staples are fed in the present types of machines except that where the member 6 remains under the central portion of the staple until the latter is partly driven, this member will only 35 support the staple strip, leaving the end staple which is to be driven projecting beyond the support. In this case the staple will be driven by the plunger 4 and the die member 5 the same as before but the central portion 40 of the staple will be supported while the prongs are being driven through the corrugated board, by the back member or rib 11 until the prongs have been driven through the corrugated board and the clenching operation has been partially completed, so that 45 the portion 11 of the strip just behind the endmost staple will be cut off just before the staple reaches the condition shown in Figure 9. In other words, the operations correspond 50 with those first described except that the temporary support 6 does not project under the staple which is being driven but only under the rib 11 just behind this staple.

The invention, as far as the product is concerned, consists of the staple or strip of staples having an intermediate portion on each 55 side of which is an arched prong, the prongs being adapted to be bent downwardly toward the plane of the central portion so that the prongs are simultaneously passed through the material to be stapled and are clenched on the inner side. In so far as the method is concerned, it consists of driving a staple through the material by operations performed entirely on one side of the material 60 for the purpose of causing the prongs of

the staple to pierce the material and clench on the reverse side.

Having described my invention, what I claim is:

1. A method of driving staples, consisting of applying pressure to a staple having arched prongs to flatten a portion thereof on one side of the material and confining the lateral positions of said prongs to cause them to pierce the material to be stapled and to 70 clench on the under side thereof, said several operations being performed exclusively from one side of the material being stapled.

2. A method of driving staples which consists in applying driving action to the top of a staple having arched prongs to flatten a portion thereof on one side of the material and to cause the prongs to pass through the material being stapled, and laterally guiding the prongs of the staple from the same side of the material that the driving force is applied, to cause the prongs of the staples to 80 clench as they pass through the material.

3. A method of driving staples consisting of applying pressure to a staple having arched prongs, said pressure being applied in a direction toward the material to be 85 stapled and simultaneously providing abutments to prevent the lateral spreading of the prongs of the staple while said pressure is being applied, to cause the prongs of the staple to pierce the material and to clench on the opposite side thereof while that portion of the staple to which pressure is being applied is being straightened against the material, said several operations being performed on one side of the material which is being stapled.

4. A method of driving staples which are formed with an intermediate portion and with prongs extending at arched shape from the opposite sides of said intermediate portion, which method consists of applying pressure to the arched prongs of said staple, simultaneously supporting the under side of 95 said intermediate portion of the staple, said pressure being applied in a direction toward the material to be stapled, and simultaneously providing abutments to prevent the lateral spreading of the prongs while said pressure is being applied, to cause the prongs of the staple to pierce the material and to clench on the opposite side thereof, said several operations being performed all on one side of the material which is being stapled.

5. A method of driving staples, consisting of applying a staple to a member to be pierced thereby, said staple having prongs extending upwardly from the middle portion of the staple and thence downwardly in arcuate shape, and applying pressure to the prongs of the staple to flatten portions thereof against one side of the material being 100 stapled, causing the prongs to pierce the material and the arcuate portions of the 110

prongs to pass into the material in arcuate paths by reason of the said straightening action of portions of the prongs, whereby said prongs will clench automatically when driven, said operations being performed exclusively from that side of the material from which the prongs enter the same.

5
Signed at the city, county, and State of New York this 7th day of January, 1929.
